UNITED STATES PATENT OFFICE.

WILLIAM GREENE DE RAMUS, OF PETRONIA, ALABAMA.

COTTON-PRESS.

No. 852,825.

Specification of Letters Patent.

Patented May 7, 1907.

Application filed May 31, 1906. Serial No. 319,624.

To all whom it may concern:

Be it known that I, WILLIAM GREENE DE RAMUS, a citizen of the United States, residing at Petronia, in the county of Lowndes and 5 State of Alabama, have invented a new and useful Cotton-Press, of which the following is a specification.

This invention relates generally to cotton presses, and more particularly to a novel 10 form of scale attachment and weight indicator combined therewith.

The object of the invention is to provide 15 simple and ready means whereby a ginner can produce bales of uniform size and weight, in which danger of breaking the press by over-feeding is obviated, and in which remnants or small bulks of cotton belonging to several 20 owners may be combined in one bale and each owner know precisely the amount of cotton included.

With the above and other objects in view, as will appear as the nature of the invention is better understood, the same consists in the 25 novel construction and combination of parts of a scale attachment and weight indicator for cotton presses, as will be hereinafter fully described and claimed.

In the accompanying drawings forming a 30 part of this specification, and in which like characters of reference indicate corresponding parts:—Figure 1 is a view in side elevation of a cotton press exhibiting the improvements of the present invention combined therewith. Fig. 2 is a view in end elevation. Fig. 3 is a sectional detail view taken on the line 3—3, Fig. 1 and looking in the direction of the arrow thereon. Fig. 4 is a transverse sectional view taken on the line 4—4, Fig. 2 and looking in the direction of 40 the arrow thereon. Fig. 5 is a sectional detail view, taken on the line 5—5 in Fig. 1.

The frame of the press, in this instance comprises a pair of longitudinal sill beams 1, four standards or supports 2, and two top 45 beams 3. The uprights are connected and braced intermediate of their ends by tie-beams 4 of which there are four employed in this instance, although it is to be understood that the invention is not to be limited to this 50 number.

The sill beams have rigidly secured to them a pair of beams 5 carrying a threaded nut 6 provided with a gear wheel 8 whereby it may be operated, and engaging a screw 7 55 carrying a follower 9.

The press box, as usual, is an open-work

rectangular structure comprising slats 10 that are secured near their lower ends to longitudinal and transverse braces 11, and 12 respectively, and near their upper ends to similar braces 13 and 14, respectively. The press box is mounted for swinging movement between the uprights and is held out of contact therewith and limited in its movements by links 15 secured to the uprights and 60 to the ends of the respective braces 11, 12, 13 and 14. The frame of the press is still further braced by tie-rods 16 rigidly attached to the upper and lower cross beams 1 and 3. The parts, so far described, may be of the character in common use, and their exact construction forms no essential part of the present invention.

The present improvements reside in a novel 75 form of scale beam for supporting the press box and a novel form of indicator or scale co-acting therewith. The scale beam portion of the invention comprises a pair of beams 17, in this instance shown as circular in cross section, although if preferred they may be 80 polygonal, near each end of each of which is secured a pair of eyes 18, through which passes a pin 19 that is engaged by the eye of a shackle 20, the crest or bend of which rests upon a knife edge bearing 21 carried by a 85 bail 22. It will be understood that there is a counterpart of this arrangement at each corner of the upper portion of the press, so that a description of one will serve for all.

Secured to each beam and projecting radially at approximately right angles to the eyes 18 is a pair of arms 23, one being located adjacent to each end of each of the beams, and these arms are engaged by the upper ends of pairs of rods 24 provided with knife 90 edge bearings 25 to work upon the arms. The lower ends of the rods engage adjustable eye bolts 26 that project through the braces 13 and carry at their lower ends adjusting nuts 27 by which to effect proper adjustment of the press box supported thereon. Each beam carries at one end a lever 28, the two levers being combined with the beams in any preferred manner and projecting inward approximately to the center of the 100 press and carry downward extending cone-shaped bearings 29 that are designed to engage similarly shaped recesses or depressions 29' in a pair of plates 30 carried by shackles 31 that engage with a ring or eye 32 combined with the lower end of the rack bar or member that actuates the pointer 33 of the 105

110

indicator mechanism which may be of any preferred construction, such as commonly used in spring balance scales. The indicator mechanism is housed in a casing 34
5 that is suitably supported by uprights 35 secured to one of the cross beams 3.

It will be seen from the foregoing description that by the manner of supporting the press box upon the beams 17, that it will be
10 free to have a limited range of vertical movements, and by the manner of combining the levers 28 with the shackles 31, free vibratory movement of all the parts may be had without interfering with the indicating mechanism.
15

Arranged within the press box is a head 36 which is supported by two cross pieces 37 secured within the box, and receives the weight of the cotton, while the follower 9 is
20 adapted to move to and from the press box as may be necessary in the operation of the machine to lift the head, and effect compression.

In the foregoing, the invention has been
25 shown as applied to a single-box press of ordinary construction; it will be understood that the invention may with equal readiness be applied to double presses, such as are now most frequently employed; and it is to be
30 distinctly understood that the right is reserved to apply the invention to double as well as to single presses.

By the arrangement of scale and indicating mechanism shown, bales of uniform
35 weight and size may be produced, and fur-

ther, where several bulks of cotton are placed in the press, each belonging to a different owner, accurate record may be kept of the cotton so pressed.

I claim:—

1. In a baling press, the combination with the press box, of a scale, a pair of beams operatively connected with the press box, levers carried by the beams, and connections between the levers and the scale. 40

2. In a baling press, the combination with a frame and a press box supported thereby, of a pair of beams carried by the frame, connections between the beams and the press box, a scale, and levers carried by the beams 45 and operatively connected with the scale.

3. In a baling press, the combination with a frame and a press box supported for limited vertical movements relatively thereto, of knife edge bearings supported by the frame, 55 a pair of beams carrying shackles that engage the knife edge bearings, levers carried by the beams, knife edge bearings carried by the opposed terminals of the levers, a scale, and shackles operatively connected with the rack bar of the scale and carrying plates with which the knife edge bearings of the levers engage.

In testimony that I claim the foregoing as my own, I have hereto affixed my signature 60 in the presence of two witnesses:

WILLIAM GREENE DE RAMUS.
